UNITED STATES PATENT OFFICE.

JOHN TOOLE, OF KIRKLAND LAKE, ONTARIO, CANADA.

SHOEMAKER'S LAST.

Application filed December 19, 1927. Serial No. 241,110.

This invention relates to lasts of the kind which are used for supporting boots while repairing the same and more particularly to a last for supporting skating boots while drilling holes therein for riveting skates thereto.

In the process of riveting skates to boots, holes are first bored through the sole of the boot at the desired spots, which vary according to the size and shape of the skate and boot and copper rivets are then driven through the boot and their ends are displaced to fasten the skate securely to the boot. When an ordinary shoemaker's last is used, the drill point is frequently blunted by contact with the last. The object of my invention is to construct a last of the kind described in which the possibility of the drill point contacting with the last is reduced to a minimum, and which will not damage the drill point if contact does occur.

I obtain my object by constructing a last of skeleton form comprising a post, a longitudinal member, and a plurality of lateral members having chisel edges where they contact with the boot.

The construction is hereinafter described and illustrated in the accompanying drawings in which

Fig. 1 is a plan view; and

Fig. 2 a side elevation in section a boot in position on the last.

In the drawings like numerals of reference indicate corresponding parts in the different figures.

1 is the lower portion or supporting member which is provided with a rectangular socket therein adapted to fit on any shoemaker's jack 2. 3 is a post which is secured to the supporting member, and 4 is a longitudinal member which is secured to the post 3. This longitudinal member may be constructed in different lengths to fit various sizes of boots. The longitudinal member is comparatively narrow for the purpose hereinafter set forth, and comparatively large on its vertical dimension to provide strength therefor.

Lateral members 5^a, 5^b and 5^c extend from the longitudinal member. These extend substantially the width of the interior of the boot and serve to support the same. They are substantially V-shaped, tapering to a chisel point at their upper sides where they are

adapted to contact with the boot. Lateral members 5^a and 5^b are forward of the post 3 and are adapted to support the front of the boot, while lateral member 5^c is to the rear of the post and supports the heel. While three lateral members are shown, any number may be used, and these may be arranged at points where it is least likely that holes may be bored through the boot.

In operation the shoemaker places the boot 6 upon the last, as shown in Fig. 2. The boot may be strapped to the jack for security. Places at which holes for the rivets are to be bored are marked, and the holes are bored with a drill. The longitudinal member 4 runs down the centre of the boot, where no holes will be bored. The lateral members 5 are well spaced and are tapered to a fine point, where they contact with the boot so that there is little danger of the drill contending with one of them. If it does so, the chisel point will cause the drill to glance off and no damage will be done. There is usually a small amount of space between each end of the last and the boot, and if the drill strikes a lateral extension, the only result would be that the boot might shift slightly relative to the last.

Although one particular form of the invention has been described, it is apparent that the form thereof may be considerably varied, and I do not desire to confine myself to the construction shown.

What I claim is:

1. A last including a plurality of spaced sole supporting members having narrow contacting edges for engaging a boot supported by the last; and means connecting said sole supporting members, the spaces between the sole supporting members being of sufficient depth to provide a passageway for the point of a drill used for boring holes in a boot supported on the last.

2. A last including a plurality of spaced sole supporting members having narrow contacting edges for engaging a boot supported by the last; and a central longitudinal member connecting said sole supporting members, the spaces between the sole supporting members being of sufficient depth to provide a passageway for the point of a drill used for boring holes in a boot supported on the last.

3. A last including a plurality of substan-

tially inverted V-shaped spaced sole support-
ing members having their apexes adapted to
engage the insole of a boot supported by the
last; and means connecting said members.

5 4. A last including a plurality of laterally
extending parallel spaced sole supporting
members having narrow contacting edges for

engaging a boot supported by the last; and
a central longitudinal member connecting
said sole supporting members.

Signed at Kirkland Lake, Ont., this 5th day
of December, 1927.

JOHN TOOLE.
